UNITED STATES PATENT OFFICE

LUCIAN E. PARKER, OF WADSWORTH, OHIO, ASSIGNOR TO THE OHIO MATCH COMPANY,
OF WADSWORTH, OHIO, A CORPORATION OF OHIO

VENDING MACHINE

Application filed June 23, 1927. Serial No. 200,935.

In the vending of small articles, such as book matches and small boxes of matches, by means of vending machines, it is customary to fill the hoppers of such vending machine by taking the articles from the containers in which they are packaged and placing them in order in such hoppers.

This is a tedious and time-consuming operation, and in the case of book matches, unless the books are properly and carefully arranged in the hoppers of the machines, they will not feed therefrom properly when the machine is operated.

It is the object of my invention to provide a vending or dispensing machine, particularly for dispensing book matches and small boxes of matches, such as the ordinary and well known boxes of safety matches, which is designed to receive in its hopper the full or original package of such articles.

I am aware that paper drinking cups, particularly of the flat type, have been loaded into dispensing machines therefor, by packaging the cups in containers so constructed that the whole package, including the container may be inserted in the machine, but in devices of this character no means are provided for mechanically feeding the cups from the machine, and obviously, therefore, such machines are not in the same category as machines such as mine, wherein mechanical means are provided for ejecting the articles from the hopper and from the container inserted therein.

Under the prevailing practice, book matches are packed in nested arrangement edgewise in cardboard boxes having closed ends, sides and bottoms and removable covers, and my machine is designed to receive in its hopper a complete box of this type with the books of matches therein, but with the cover or lid removed, the books being ejected from the hopper and the box therein by appropriate mechanical ejecting mechanism.

In its broad aspect, the invention consists in a vending or dispensing machine having a hopper adapted to receive a package of the articles to be vended or dispensed, including the container in which the articles are packed, means being provided in combination

therewith for ejecting or feeding the articles directly therefrom mechanically to a delivery point, as I will proceed now to explain and finally claim.

In the accompanying drawings illustrating the invention, in the several figures of which like parts are similarly designated, Figure 1 is a perspective view of the complete machine of my invention. Fig. 2 is a perspective view of a complete package of book matches such as may be used in the hopper of my machine, a part of the lid or cover thereof being broken away to show the arrangement of the match books therein. Figs. 3 and 4 are fragmentary views illustrating two ways in which the containers may be prepared for use in my machine. Fig. 5 is a fragmentary sectional elevation of the machine with the hopper thereof loaded with match books. Fig. 6 is a view similar to Fig. 5, but showing the machine modified to adapt it for the vending or dispensing of boxes of matches. Fig. 7 is an enlarged fragmentary sectional side elevation of the machine. Fig. 8 is a fragmentary view similar to Fig. 7 but showing the position of the articles in the hopper during the ejecting operation. Figs. 9 and 10 are enlarged fragmentary detail views illustrating one aspect of the operation of the ejector bars. Fig. 11 is a horizontal section taken on line 11-11 of Fig. 7 on a smaller scale, parts thereof being broken away to show the mechanism beneath. Fig. 12 is an enlarged fragmentary detail view of the check-controlled members of the ejector mechanism. Fig. 13 is an enlarged perspective view of the check-actuated stop member. Fig. 14 is an enlarged detail perspective view of the ejector mechanism and associated parts.

The machine has a base 1, and a hopper 2 rigidly mounted upon the base and having an open upper or loading end 3 provided with a suitable cover 4 which may be hinged or otherwise mounted and secured in place by a tongue and lock mechanism 5, or other means which will prevent unauthorized access to or tampering with the contents of the hopper.

The base 1 is provided with a top portion 6

55

90

95

100

which forms a surface upon which the articles, including their container, positioned in the hopper 2, may be supported and upon which such articles may be ejected.

- 5 The ejector mechanism (Figs. 7 to 14) has a slide member 7 preferably of channel formation to provide a finger hold, from the ends of which extend rigid link members 8 having slides 9 which normally engage with slide-
10 ways 10 in the sides of the base 1. The rear ends 11 of the link members 8 have secured between them, in any appropriate manner, a cross member 12 carrying a plurality, preferably four, of ejector bars 13 provided with sharpened leading ends 14 and having barbs or prongs 15 formed in their sides, for a purpose later explained.

Depending from the cross member 12 is a boss 16 carrying an arm 17 to the forward end 20 of which is fixed a check or coin holder 18 which directly underlies a complementary slot 19 in the slide 7, and directly beneath the cross member 12 is a forwardly extending flat strip 20 which slides in a complementary slot 21 in the top 6 of the base 1.

Within the base 1 is mounted a stand 22 having a projecting arm 23 over which the check or coin holder 18 slides and which normally closes the coin or check-holding slot 30 of the holder. Also carried by this stand 22 is a spring latch member 24 controlled by a key or otherwise actuated lock 25, and this latch member engages a coin tray 26 which rests upon the bottom 27 of the base 1 and carries a plate 28 which closes the front end of the base.

Carried by the plate 28 is a spring stop member 29 (Figs. 7, 12 and 13) provided with stops 30 and cam members 31.

40 By reference to Figs. 12, 13 and 14, it will be seen that the coin slot 32 of the check or coin holder 18 extends through the holder from top to bottom, and also that the holder is recessed upon its sides to form lugs 33 and depressions 34. The lugs 33 are adapted to engage with the stops 30 of the stop member 29, and the cam members 31 normally lie in juxtaposition to the depressions 34.

50 The front of the hopper 2 at its lower end is provided with an opening 35 of a height sufficient to permit the passage through it of the lowermost of the articles contained in the hopper. This opening is normally closed by one of the flanges 36 of the slide member 7.

55 The back of the hopper is provided with openings 37 through which the ejector bars 13 may pass. Sight openings 38 are formed in the hopper front so that the contents may be seen and the need for replenishment noted.

60 A suitable cover plate 39 is provided for covering the ejector mechanism.

The operation of the device is as follows:—

It will be noted first that the machine is designed to vend two books of matches or other articles at one operation of the ejector

and upon the depositing of a single check or coin in the coin slot.

The hopper is filled by removing the lid or cover 40 from a package of match books such as shown in Fig. 2, and inserting this full package of match books, box included, in the hopper, with its open top toward the front of the hopper. This box forms the subject of my copending application filed August 29, 1927, Serial No. 216,104:

70 In order that the ejector bars 13 may easily pass through the bottom 41 of the box, I may provide therein appropriately located openings 42 for their reception, or I may partially sever disks similarly located, as indicated at 43, Fig. 4, same being removed before the package is inserted in the hopper. However, as already pointed out, it is not necessary that any provision be made for the 75 passage of the ejector bars 13, and therefore the box may have its bottom intact, the ejector bars being capable of forming their own 80 openings therein.

85 With the hopper thus filled, and the parts in the positions of Fig. 7, the machine is ready 90 to operate. In order to obtain the books of matches from the machine, the purchaser deposits his check or coin, say one cent, in the slot 19. The coin drops through this slot and a similar registering slot 19' in the top 95 6 of the base, and falls into the slot 32 of holder 18, being prevented from passing therethrough by the arm 23. It will be apparent, by reference to Figs. 5, 6 and 12, that the coin when in this position extends beyond 100 the edges of the depressions 34. By pulling upon the flange 36 of the slide member 7 the coin will come in contact with the cam members 31 and will spread them apart, at the same time spreading apart the stops 30 upon 105 opposite sides so that they will not be in the path of movement of the lugs 33 of the coin holder 18. The stops being thus moved out of the way the slide may be moved to the position shown in Fig. 8, the coin falling into 110 the tray 26 when it clears the end of arm 23. As the slide is moved forward, it carries with it the rest of the ejector mechanism shown in Fig. 14, the ejector bars 13 pushing forward the two lowermost books of matches of the 115 two stacks, and the strip 20 sliding in the depression 21 and filling same flush with the rest of the top 6, and covering the coin slot 19' in the top.

120 As will be seen by reference to Fig. 8, the next two books of matches in order rest upon the ejector bars 13 and are held thereby in such position that they cannot escape from or be extracted through the opening 35.

125 Obviously, if the types of boxes shown in Figs. 3 and 4 are used, the ejector bars 13 merely pass through the openings 37 in the back of the hopper and through those in the box, but if openings have not already been formed in the box, the bars 13 will, by means 130

of their sharp ends 14, puncture or pierce the box. In thus puncturing or piercing the box, lips or tabs of cardboard are almost sure to be formed, as shown in Fig. 9, and these would arrest the descent of the stacks of match books, upon withdrawal of the bars 13 from beneath them, were it not for the provision of the prongs or barbs 15 which engage with these tabs and pull them back into the openings 37 in the back of the hopper, as shown in Fig. 10.

It will be apparent that the coin is the operating link in the mechanism for the reason that lacking its presence in the holder 18, the stops 30 limit movement of the ejector mechanism, and a coin cannot be inserted unless the parts are in the positions shown in Figs. 1, 7, 11 and 12, because when in any other position the coin slot 19' in the top 6 of the base is covered and closed by the strip 20. Thus, before the machine can be operated to obtain matches, it is necessary, if the slide is left as shown in Fig. 8, to push it back to the position of Fig. 7.

When it is desired to empty the coin tray, the latch 24 is lifted by insertion and turning of a proper key in the lock 25, then the front plate 28 is pulled out and the tray 26 comes with it.

I have described particularly the vending or dispensing of book matches, but, as hereinbefore indicated, the machine may be adapted for use with boxes of matches or other articles, the only changes necessary being the proper proportioning of the various parts, particularly the opening 35 and flange 36, and the positioning and conformation of the ejector bars 13.

Also, I have shown and described in some detail a particular arrangement of check or coin-controlled ejector mechanism, but this might be replaced by other forms of such mechanism within the purview of my invention, the main feature of which is a machine of this or like character wherein provision is made for the reception of a whole package of articles to be vended or dispensed, container and all, and in means for automatically feeding the articles from the container while same is in the machine. By these means I do away with the laborious transferring of a great number of small articles from a package to the hopper of a vending or dispensing machine, as is now the general practice.

As shown, my machine is designed to handle two stacks of superposed articles, but obviously it could be so modified as to handle a greater or less number of stacks.

Various other changes are contemplated as within the spirit of the invention and the scope of the following claims.

What I claim is:—

1. In a vending machine and the like provided with a hopper, a supplementary hopper, the said supplementary hopper being the

original container of the articles to be vended, and means for ejecting said articles from said supplementary hopper.

2. In a vending machine and the like provided with a hopper, a supplementary hopper, the said supplementary hopper being the original container of the articles to be vended, and means including ejector members adapted to pass through said supplementary hopper for ejecting said articles therefrom. 70

3. In a vending machine and the like provided with a hopper, a supplementary hopper, the said supplementary hopper being the original container of the articles to be vended and in which said articles are arranged in a plurality of rows, and means for ejecting said articles from said supplementary hopper, said means being aligned with said rows. 80

4. In a vending machine and the like provided with a hopper, a supplementary hopper, the said supplementary hopper being the original container of the articles to be vended, said supplementary hopper provided with a plurality of apertures in one of its sides, and an ejector provided with devices 85 for entering said apertures to eject said articles.

5. In a vending machine and the like, provided with a hopper, a supplementary hopper, said supplementary hopper being the original container of the articles to be vended and in which said articles are arranged in a plurality of rows, an aperture in one side of said supplementary hopper in line with each of said rows, and an ejector provided with 95 devices for entering said apertures to eject said articles. 100

6. In a vending machine and the like provided with a hopper, a supplementary hopper, said supplementary hopper being the original container of the articles to be vended and in which said articles are arranged in a plurality of rows, an aperture in one side of said supplementary hopper in line with each of said rows, and an ejector provided with 105 devices for entering said apertures to eject one article from each of said rows simultaneously. 110

7. In a vending machine and the like, a hopper adapted to receive a package of articles, including the container, and an ejector mechanism including an ejector bar adapted to penetrate said container to eject said articles therefrom in regular order. 115

8. In a vending machine and the like, a hopper adapted to receive a package of articles, including the container in which the articles are arranged in a plurality of rows, and an ejector mechanism including an ejector bar adapted to penetrate said container 120 in line with each of said rows to eject said articles therefrom in regular order.

9. In a vending machine and the like, a hopper adapted to receive a package of articles, including the container, and an ejector 125

mechanism including an ejector bar adapted to penetrate said container to eject said articles therefrom in regular order, said bar being provided with means for clearing the opening in said container formed by its penetration thereof.

In testimony whereof I have hereunto set my hand this 21st day of June, A. D. 1927.

LUCIAN E. PARKER.
